United States Patent Office.

JOHN A. BLAKE OF NEW HAVEN, CONNECTICUT, ASSIGNOR TO BLAKE BROTHERS, OF SAME PLACE.

Letters Patent No. 62,925, dated March 19, 1867.

INK-WELL COVER.

The Schedule referred to in these Letters Patent and making part of the same.

TO ALL WHOM IT MAY CONCERN:

Be it known that I, JOHN A. BLAKE, of New Haven, in the county of New Haven, and State of Connecticut, have invented a new improvement in Ink-Well Covers; and I do hereby declare the following, when taken in connection with the accompanying drawings and the letters of reference marked thereon, to be a full, clear, and exact description of the same, and which said drawings constitute part of this specification, and represent, in—

Figure 1 a top view.

Figure 2, a side view.

Figure 3, a section on line xx .

Figure 4, the cover detached to show its construction.

Figure 5, a top view of the common ink-well cover; and in

Figure 6, a section of the same on line YY .

Heretofore the hinge of the cover has been formed by the insertion of a pintle, as in common butt hinges. This formation of the hinge occasions a large part of the cost of manufacture. To simplify the construction of the hinge, thereby reducing the cost of manufacture, is the object of my invention, which consists in forming the pintle upon the cover itself, and a hooked shank, which, placed over the pintle so formed, securely holds the cover and forms the hinge.

To enable others to construct and use my improvement, I will proceed to describe the same as illustrated in the accompanying drawings. First, I will describe the cover as heretofore constructed, and as shown in figs. 5 and 6.

A is the cover, formed with two ears, a ; B the shank, formed with a single ear, d , corresponding to the ears a , and fitted closely between the two ears, as seen in fig. 5, and in like manner as the ordinary butt hinge. Through the three ears a hole is centrally bored, into which the pintle f is placed and riveted, so that when the shank is secured, as seen in fig. 5, the cover may be easily opened and closed.

It will be readily seen that the mechanical operation required to hinge the cover to the shank is the chief cost in the manufacture. By my invention this expense is entirely avoided, in the manner which I will now proceed to describe.

C is the cover, of the common or any desired form or design. Upon one side I form two projecting ears, b , joined by a bar, c , (see fig. 4,) which said bar, between the two ears, is formed round, and so as to leave an opening, e , between the said bar and the cover. The said bar and the ears are formed from the same piece as the cover, and generally made from cast metal. D is the shank, provided with screw holes, i , by which it is secured to the desk in the usual manner. Upon the said shank, and in one and the same piece, is formed a hook, E, corresponding in width to the opening e in the cover, and the hook formed so as to set over the bar c , as seen in figs. 1 and 3; and when thus set over the bar and secured to the desk the cover may be freely opened or closed, as denoted in fig. 3; thus the hinge is formed without other mechanical operations than that required to form the cover and shank, whereby I reduce the cost of manufacture by so much as the labor required to form the hinge first described.

Having, therefore, thus fully described my invention, what I claim as new and useful, and desire to secure by Letters Patent, is—

The combination of the cover C and the shank D, when hinged together by a hook formed upon the one, and a corresponding bar on the other, substantially in the manner herein set forth.

JOHN A. BLAKE.
